ATTORNEY

UNITED STATES PATENT OFFICE

PETER C. A. VANDER MEER, OF DETROIT, MICHIGAN, ASSIGNOR TO SNAX AUTOMATIC STORES, INC., OF DETROIT, MICHIGAN, A CORPORATION OF MICHIGAN

COIN CONTROL

Application filed October 8, 1930. Serial No. 487,125.

My invention relates to a coin control device and more particularly to coin detectors for use in coin control devices.

Coin control devices having weight-bar coin detectors of this general class have heretofore been used. It has been found, however, that devices of this general type have not been adapted for use in small vending machines for the reason that the slight tilting or tipping of these machines renders the device inoperative due to the change of angle of the weight bar. It also has been found that a weight bar coin detector made to operate on the heavier coins is not sensitive enough 10 to operate successfully with lighter coins, such as dimes. If made sensitive enough to operate with the lighter coins, much difficulty is experienced in adjusting it for use with heavier coins.

It is, therefore, an object of my invention to provide a coin control device having a weight bar coin detector which is so arranged as to be unaffected by any tilting of the vending machine in which it is a part, thus rendering 25 it useful in smaller vending machines.

It is a further object of my invention to provide a coin control device having a weight bar coin detector, which is adjustable to control the sensitivity of the weight bar, thus 30 permitting the same device to be used in coin control vending machines which may be used at different times with coins of different denominations.

It is a further object of my invention to provide a coin control having a coin detector which is so constructed as to permit necessary 35 adjustments in the coin chutes when the device is to be used with coins of varying denominations.

With these and other objects in view, my invention consists in the construction, combination and arrangement of parts as will be hereinafter more fully described and as illustrated in the accompanying drawing, in 40 which

Fig. 1 is a plan view in front elevation of the coin controlled vending machine with one side removed to show the coin control mechanism;

Fig. 2 is a cross sectional view in side elevation taken on the line 2—2 of Fig. 1;

Fig. 3 is a detailed plan view of the coin control lock shown in Fig. 1;

Fig. 4 is a detailed view in cross section 55 of the pivots for the coin detector bar shown in Fig. 1;

Fig. 5 is a detailed plan view of the coin chute adjusting plate shown in Fig. 2;

Fig. 6 is a detailed view in cross section 60 taken on the line 6—6 of Fig. 5;

Fig. 7 is a detailed view partially in cross section of the mounting on a vending machine for the coin control mechanism.

Similar reference numerals refer to similar 65 parts throughout the several views.

Referring more in detail to the drawing, 8, 9 and 10 designate three of the side walls of a coin controlled vending machine (not shown completely). It is to be understood 70 that such a vending machine may be of any particular type which has a delivery mechanism operated through a shaft 11. While any desired form of coin control lock may be used on a shaft such as the shaft 11, one 75 form of such lock being shown in the drawing comprises a plate 12, having ratchets 13, which is keyed to the shaft 11 by the key 14. The plate 12 has a rib 15 which contacts with a spring actuated locking dog 16. A 80 spring actuated pawl 17 cooperates with the ratchets 13 to prevent a backward rotation of the plate 12 and the shaft 11. The plate 12 has a pocket 18 for receiving a coin 19. When the coin 19 has been deposited in the 85 pocket 18, the coin projects beyond the outer edge of the plate 12 and acts to raise the spring actuated locking dog 16 sufficiently to prevent its contact with the rib 15 of the plate 12.

Coins are delivered to the coin pocket 18 in the plate 12 through an upper coin delivery chute 20, formed between a cover 20^a and a plate 27, and a side coin chute 21, having a weight bar coin detector 22 separating said side coin delivery chute from the lower coin delivery chute 23. Coins passing through the coin chute 20, not deflected by the magnet 26, are stopped by a flange formed on the plate 27 which extends inside the chute 90 95 100

20 adjacent the mouth of the side coin chute 21, the said flange being inclined toward said side coin chute 21. Coins coming in contact with said flange, roll directly from said chute 20 to said side coin chute 21. In order to separate spurious coins or coins of improper denominations from the coins which are admitted into the lower coin chute 23, slug expelling chutes 24 and 25, communicating 10 with a slug outlet, are provided. The slug expelling chute 24 is placed directly beneath the upper coin chute 20 and communicates with the forward end of the side coin chute 21, while the slug expelling chute 25 connects 15 with the opposite end of the side coin chute 21. Mounted on the cover 20a of the upper coin chute 20, is a magnet 26 for detecting coins having a high content of material affected by magnetic action.

20 All of the coin control mechanism is mounted on a plate 27, having four ears 28 at the four corners of the said plate, the ears 28 being provided with holes 29 for receiving pins 30, which are mounted on the sides 25 8 and 9 of the coin controlled vending machine, the holes 29 in the ears 28 being larger than the pins 30 so as to permit movement of the entire plate relative to the sides of the coin controlled vending machine. At the 30 lower edge of the plate 27 there is secured a weight 32, which is so secured as to act as a pendulum to maintain the plate 27 in a relatively constant position regardless of slight movements of the coin controlled vending machine.

35 The side coin chute 21 comprises a plate or cover 33, having elongated slots 34 and 35 and a weight bar adjusting screw 36. Also mounted on the cover 33 are two projections 40 such as the projection 37 for forming the support for the pivots on both ends of the weight bar 22. The weight bar 22 is mounted on adjustable pivot points 38 and 39 and has a projection 40 which contacts with the point of 45 the adjusting screw 36 to regulate the amount of movement of the weight bar 22. A counter weight 41 is provided in order to adjust the weight bar 22 for coins of various weights. The weight bar 22 is provided at each end 50 with recesses, such as the recess 42 shown in Fig. 4. Jewels 43 are placed in each of said recesses, and furnish seats for the points of the adjustable pivot members 38 and 39.

55 The side coin chute 21 may be adjusted to compensate for the thickness of various coins by adjustment of the back plate 44 movable in a recess 45 in the plate 27. The back plate 44 comprises a projection 46 and is adjusted by means of adjusting screws 47, 48, 49 and 60 50 and holding screws 51 and 52.

The operation of my invention is as follows:

65 Assuming that a coin of a proper denomination has been placed in the coin controlled vending machine, and has reached the upper

70 coin slot 20, such a coin will roll into the side coin chute 21 and onto the weight bar 22, the weight bar 22 having been so adjusted that the coin of a proper denomination will tilt the weight bar at such a time as to drop the 75 coin into the lower coin chute 23, which delivers the coin to the coin pocket 18 in the plate 12 of the coin lock keyed to the operating shaft 11. When the coin has been placed in the coin pocket 18 of the plate 12, and the shaft is rotated, the coin contacts with the spring actuated locking dog 16 and raises it so that the plate 12 is free to rotate with the shaft 11. This permits the operation 80 of the delivery mechanism of the coin controlled vending machine. During the time that the plate 12 is being rotated with the shaft 11, when the proper coin is in the pocket 18, the spring actuated pawl 17 contacts with the ratchets 13 on the plate 12 and prevents a backward rotation of the shaft 11.

85 Assuming that a coin containing a high percentage of material responsive to magnetic influence, such as an iron or steel slug, is placed in the coin controlled vending machine and reaches the upper coin chute 20, the magnet 26 tends to draw such a coin toward it and the coin is then deflected into the slug expelling chute 24 and drops through 90 this chute and out of the machine.

95 If a coin which is of too heavy a weight is placed in the machine, the coin will drop through the upper coin chute 20 and into the side coin chute 21, but its weight will be such as to tilt the weight bar 22 as soon as the coin reaches the forward end thereof. This drops such a coin into the projection on the coin chute 24 and such a coin is conducted through the slug expelling chute 24 and out of the 100 machine.

105 If a coin which is too light has been placed in the machine, it will drop through the upper coin chute 20 into the side coin chute 21, but is not of a sufficient weight to tilt the weight bar 22 and rolls beyond the lower end 110 of the weight bar 22 and into the slug expelling chute 25, through which it is taken out of the machine.

115 It will be apparent from the foregoing that the efficiency of the coin detection mechanism which I have employed in my coin control device, will be greatly impaired by a change of the inclination of the side coin chute 21 and the weight bar 22. In order to compensate for the usual tilting of the coin controlled vending machine, and in order to maintain the side coin chute 21 and the weight bar 22 at the predetermined angle relative to the side of the coin controlled vending machine, the plate 27 is supported by the operating shaft 11, but is free to rotate around said shaft and said shaft may be rotated without affecting the said plate 27. The plate 27, being loosely mounted on the projections 31 and the pins 30 on the sides of the coin controlled vending 120 125 130

machine, and being free to rotate around the shaft 11, is maintained in a relatively constant position due to the action of the weight 32 acting as a pendulum and tending to restore the plate 27 to its original position regardless of momentary displacement due to tilting of the vending machine.

In order to provide one coin control which may be adjustable to take various sizes of 10 coins, the slots 34 and 35 in the cover 33 of the side coin chute 21 permit the adjustment of the pitch or inclination of the coin chute 21 and the weight bar 22. The weight bar 22 may be adjusted to act on coins of different 15 weights by an adjustment of the counter weight 41. The adjusting screw 36, acting on the projection 40 of the weight bar 22, may be adjusted to control the extent to which the weight bar 22 is permitted to pivot to 20 drop any particular coin. To provide for coins of various thicknesses the adjustable plate 44, at the rear of the coin chute 21, may be so adjusted that the projection 46 will leave sufficient space between the cover 33 of 25 the side coin chute 21 to permit the passage of a thin coin, such as a dime, or it may be withdrawn so as to provide a wider passage to permit the passage of thicker coins, such as twenty-five cent pieces.

30 While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what 35 I claim is new and desire to secure by Letters 40 Patent of the United States, is:—

1. The combination with a coin controlled vending machine of a coin control device having a coin receiving chute and a slug expelling chute, and a coin detector comprising a 45 tilting platform intersecting the path of said coin receiving chute and means pivotally mounting the said platform whereby said platform will tilt on the contact at one end thereof of a coin of a predetermined weight and will tilt also on contact at the other end 50 thereof of a coin of a different weight whereby a coin of a predetermined weight will be separated from coins of other weights, and means whereby said tilting platform will be maintained on a constant axis relative to a predetermined position of said coin controlled vending machine.

2. The combination with a coin controlled 55 vending machine of a coin control device having a coin receiving chute and a slug expelling chute, and a coin detector comprising a tilting platform intersecting the path of said coin receiving chute and means pivotally mounting the said platform whereby said platform will tilt on the contact at one end

thereof of a coin of a predetermined weight and will tilt also on contact at the other end thereof of a coin of a different weight whereby a coin of a predetermined weight will be separated from coins of other weights, and adjustable weight means for balancing said 70 platform, and means whereby said tilting platform will be maintained on a constant axis relative to a predetermined position of said coin controlled vending machine.

3. The combination with a coin controlled vending machine having a coin chute, of a coin control device having a coin detector comprising a tilting platform intersecting the path of said coin chute and means pivotally mounting the said platform whereby said platform will tilt on the contact therewith at one end of a coin of a predetermined weight, and will tilt also on the contact therewith at its opposite end of a coin of a different weight with respect to said first named coin, an adjustable weight means for balancing said 80 platform, a partition in said coin chute below said platform to form independent chambers for receiving said coins respectively, and means whereby said tilting platform will be maintained on a constant axis relative to a predetermined position of said coin controlled vending machine.

4. The combination with a coin controlled vending machine having a coin chute, of a coin control device having a coin detector comprising a tilting platform intersecting the path of said coin chute, means pivotally mounting the said platform whereby said platform will tilt on the contact therewith at one end of a coin of a predetermined weight, and will tilt also on the contact therewith at its opposite end of a coin of a different weight with respect to said first named coin, an adjustable weight means for balancing said 90 platform, a partition in said coin chute below said platform to form independent chambers for receiving said coins respectively, and means whereby said tilting platform will be maintained on a constant axis relative to a predetermined position of said coin controlled vending machine.

5. The combination with a coin controlled vending machine having a coin chute, of a coin control device having a coin detector comprising a tilting platform intersecting the path of said coin chute, means pivotally mounting the said platform whereby said platform will tilt on the contact therewith at one end of a coin of a predetermined weight, and will tilt also on the contact therewith at its opposite end of a coin of a different weight with respect to said first named coin, an adjustable weight means for balancing said 100 platform, and a partition in said coin chute below said platform to form independent 110 chambers for receiving said coins respectively.

6. The combination with a coin controlled vending machine having a coin chute, of a coin control device having a coin detector comprising a tilting platform intersecting the path of said coin chute, means pivotally mounting the said platform whereby said platform will tilt on the contact therewith at one end of a coin of a predetermined weight, and will tilt also on the contact therewith at its opposite end of a coin of a different weight with respect to said first named coin, an adjustable weight means for balancing said 120 platform, and a partition in said coin chute below said platform to form independent 130 chambers for receiving said coins respectively.

ent chambers for receiving said coins respectively, said coin chute, coin control device and coin detector being fixedly mounted on a plate mounted adjacent one side of said coin

5 controlled vending machine and adapted for movement relative to said side of said coin controlled vending machine.

6. The combination with a coin controlled vending machine having a coin chute and means for adjusting the size of said coin chute, of a coin control device having a coin detector comprising a tilting platform intersecting the path of said coin chute, means pivotally mounting the said platform whereby said platform will tilt on the contact therewith at one end of a coin of a predetermined weight, and will tilt also on the contact therewith at its opposite end of a coin of a different weight with respect to said first named coin, an adjustable weight means for balancing said platform, and a partition in said coin chute below said platform to form independent chambers for receiving said coins respectively, said coin chute, coin control device and coin detector being fixedly mounted on a plate mounted adjacent one side of said coin controlled vending machine and adapted for movement relative to said side of said coin controlled vending machine.

30 7. The combination with a coin controlled vending machine having an adjustable coin chute, of a coin control device having a coin detector comprising a tilting platform intersecting the path of said coin chute, means piv-

35. seating the said platform whereby said platform will tilt on the contact therewith at one end of a coin of a predetermined weight, and will tilt also on the contact therewith at its opposite end of a coin of a differ-

40 with at its opposite end of a coin of a different weight with respect to said first named coin, an adjustable weight means for balancing said platform, a partition in said coin chute below said platform to form independent channels of receiving and giving passage

45 ent chambers for receiving said coins respectively, said coin chute, coin control device and coin detector being fixedly mounted on a plate pivotally mounted adjacent one side of said coin controlled vending machine and

adapted for movement relative to said side of said coin controlled vending machine, and means on said plate for adjusting the size of said coin chute, said means comprising an opening in said plate and an adjustable cover member adapted to slide in said opening.

55. 8. The combination with a coin controlled vending machine having a coin chute, of a coin control device having a coin detector comprising a tilting platform intersecting the path of said coin chute means pivotally

60 the path of said coin chute, means pivotally mounting the said platform whereby said platform will tilt on the contact therewith at one end of a coin of a predetermined weight,

65 and will tilt also on the contact therewith at its opposite end of a coin of a different weight with respect to said first named coin, an ad-

justable weight means for balancing said platform, and a partition in said coin chute below said platform to form independent chambers for receiving said coins respectively, said coin chute, coin control device and coin detector being mounted on a plate mounted adjacent one side of said coin controlled vending machine and adapted for free movement relative to said side of said coin controlled vending machine, and means for regulating the pitch of said coin chute.

9. The combination with a coin controlled vending machine having a coin chute, of a coin control device having a coin detector comprising a tilting platform intersecting the path of said coin chute, means pivotally mounting the said platform whereby said platform will tilt on the contact therewith at one end of a coin of a predetermined weight, and will tilt also on the contact therewith at its opposite end of a coin of a different weight with respect to said first named coin, an adjustable weight means for balancing said platform, and a partition in said coin chute below said platform to form independent chambers for receiving said coins respectively, said coin chute, coin control device and coin detector being mounted on a plate mounted adjacent one side of said coin controlled vending machine and adapted for free movement relative to said side of said coin controlled vending machine, means for regulating the pitch of said coin chute, and means for adjusting the size of said coin chute.

10. The combination with a coin controlled vending machine having a coin chute, of a coin control device having a coin detector comprising a tilting platform intersecting the path of said coin chute, adjustable means for pivotally mounting the said platform whereby said platform will tilt on the contact therewith at one end of a coin of a predetermined weight, and will tilt also on the contact therewith at its opposite end of a coin of a different weight with respect to said first named coin, an adjustable weight means for balancing said platform, and a partition in said coin chute below said platform to form independent chambers for receiving said coins respectively, and means whereby said tilting platform will be maintained on a constant axis relative to a predetermined position of said coin controlled vending machine.

11. The combination with a coin controlled vending machine having a coin chute, of a coin control device having a coin detector comprising a tilting platform intersecting the path of said coin chute, means comprising pivot points bearing in jewelled cups for pivotally mounting said platform whereby said platform will tilt on the contact therewith at one end of a coin of a predetermined weight, and will tilt also on the contact therewith at its opposite end of a coin of a differ-

ent weight with respect to said first named coin, an adjustable weight means for balancing said platform, and a partition in said coin chute below said platform to form independent chambers for receiving said coins respectively, and means whereby said tilting platform will be maintained on a constant axis relative to a predetermined position of said coin controlled vending machine.

10 12. The combination with a coin controlled vending machine having a coin chute, of a coin control device having a coin detector comprising a magnet and a tilting platform intersecting the path of said coin chute, means pivotally mounting the said platform whereby said platform will tilt on the contact therewith at one end of a coin of a predetermined weight, and will tilt also on the contact therewith at its opposite end of a coin of a different weight with respect to said first named coin, an adjustable weight means for balancing said platform, and a partition in said coin chute below said platform to form independent chambers for receiving said coins respectively, and means whereby said tilting platform will be maintained on a constant axis relative to a predetermined position of said coin controlled vending machine.

20 13. The combination with a coin controlled vending machine having a coin chute, of a coin control device having a coin detector comprising a magnet and a tilting platform intersecting the path of said coin chute, means pivotally mounting the said platform whereby said platform will tilt on the contact therewith at one end of a coin of a predetermined weight, and will tilt also on the contact therewith at its opposite end of a coin of a different weight with respect to said first named coin, an adjustable weight means for balancing said platform, and a partition in said coin chute below said platform to form independent chambers for receiving said coins respectively, said coin chute, coin control device and coin detector being fixedly mounted on a plate having a weight attached to its lower edge, said plate and weight being mounted adjacent one side of said coin controlled vending machine.

30 14. The combination with a coin controlled vending machine having a coin chute, of a coin control device having a coin detector comprising a tilting platform intersecting the path of said coin chute, means pivotally mounting the said platform whereby said platform will tilt on the contact therewith at one end of a coin of a predetermined weight, and will tilt also on the contact therewith at its opposite end of a coin of a different weight with respect to said first named coin, an adjustable weight means for balancing said platform, and a partition in said coin chute below said platform to form independent chambers for receiving said coins

respectively, means for mounting said coin chute, coin control device and said coin detector in said coin controlled vending machine, comprising a plate mounted adjacent one side of said coin controlled vending machine, and a weight adjacent the lower edge of said plate and adapted to maintain said plate in a constant position relative to the said side of said coin controlled vending machine.

40 15. The combination with a coin controlled vending machine having a coin chute, of a coin control device having a coin detector comprising a tilting platform intersecting the path of said coin chute, means pivotally mounting the said platform whereby said platform will tilt on the contact therewith at one end of a coin of a predetermined weight, and will tilt also on the contact therewith at its opposite end of a coin of a different weight with respect to said first named coin, an adjustable weight means for balancing said platform, and a partition in said coin chute below said platform to form independent chambers for receiving said coins respectively, said coin chute, coin control device and coin detector being fixedly mounted on a plate having a weight attached to its lower edge, said plate and weight being mounted adjacent one side of said coin controlled vending machine for movement relative to said side of said coin controlled vending machine.

50 16. The combination with a coin controlled vending machine having a coin chute, of a coin control device having a coin detector comprising a magnet and a tilting platform intersecting the path of said coin chute, means pivotally mounting the said platform whereby said platform will tilt on the contact therewith at one end of a coin of a predetermined weight, and will tilt also on the contact therewith at its opposite end of a coin of a different weight with respect to said first named coin, an adjustable weight means for balancing said platform, and a partition in said coin chute below said platform to form independent chambers for receiving said coins respectively, said coin chute, coin control device and coin detector being fixedly mounted on a plate having a weight attached to its lower edge, said plate and weight being mounted adjacent one side of said coin controlled vending machine and adapted for movement relative to said side of said coin controlled vending machine.

60 17. The combination with a coin controlled vending machine having a coin chute, of a coin detector comprising a tilting platform intersecting the path of said coin chute, means pivotally mounting the said platform whereby said platform will tilt on the contact therewith at one end of a coin of a predetermined weight, and will tilt also on the contact therewith at its opposite end of a coin of a different weight with respect to said first named coin, an adjustable weight means for balancing said platform, and a partition in said coin chute below said platform to form independent chambers for receiving said coins

a different weight with respect to said first named coin, adjustable weight means for balancing said platform, means whereby said tilting platform will be maintained on a constant axis relative to a predetermined position of said coin controlled vending machine, and a partition in said coin chute below said platform to form independent chambers for receiving said coins respectively, and a coin control lock adapted to receive coins from one of said independent chambers in said coin chute.

18. The combination with a coin controlled vending machine having a coin chute, of a coin detector comprising a magnet and a tilting platform intersecting the path of said coin chute, means pivotally mounting the said platform whereby said platform will tilt on the contact therewith at one end of a coin of a predetermined weight, and will tilt also on the contact therewith at its opposite end of a coin of a different weight with respect to said first named coin, adjustable weight means for balancing said platform, a partition in said coin chute below said platform to form independent chambers for receiving said coins respectively, a coin control lock mounted on a shaft operating the delivery mechanism of said coin controlled vending machine, and comprising a plate normally held against rotation by means of a locking dog, a pocket in said plate for receiving a coin from one of said independent chambers whereby a rotation of said shaft will release said locking dog and permit the operation of said coin controlled vending machine, and means whereby said coin detector and said coin control lock will be maintained in their constant positions relative to a predetermined position of said coin controlled vending machine.

19. The combination with a coin controlled vending machine having a coin chute, of a coin detector comprising a tilting platform intersecting the path of said coin chute, means pivotally mounting the said platform whereby said platform will tilt on the contact therewith at one end of a coin of a predetermined weight, and will tilt also on the contact therewith at its opposite end of a coin of a different weight with respect to said first named coin, adjustable weight means for balancing said platform, a partition in said coin chute below said platform to form independent chambers for receiving said coins respectively, a coin control lock mounted on a shaft operating the delivery mechanism of said coin controlled vending machine, and comprising a plate normally held against rotation by means of a locking dog, and means to prevent the backward rotation of said shaft and said plate, and a pocket in said plate for receiving a coin from one of said independent chambers whereby a rotation of said shaft will release said locking dog and permit the operation of

said coin controlled vending machine, and means whereby said tilting platform will be maintained on a constant axis relative to a predetermined position of said coin controlled vending machine.

In witness whereof I hereunto subscribe my name this 6 day of October, 1930.

PETER C. A. VANDER MEER.
